UNITED STATES PATENT OFFICE.

CHARLES E. HOPKINS, OF PLAINFIELD, NEW JERSEY.

METHOD OF COOLING FINISHED STEREOTYPE PRINTING PLATES.

1,416,714.

Specification of Letters Patent. Patented May 23, 1922.

Original application filed February 25, 1911, Serial No. 610,834. Divided and application filed April 2, 1917, Serial No. 159,117. Divided and this application filed July 12, 1920. Serial No. 395,560.

To all whom it may concern:

Be it known that I, CHARLES E. HOPKINS, a citizen of the United States, residing at Plainfield, in the county of Union and State 5 of New Jersey, have invented a new and useful Method of Cooling Finished Stereotype Printing Plates, of which the following is a specification.

This is a division of my application Serial 10 No. 159,117 filed April 2, 1917, which was a division of my application filed February 25, 1911, Serial No. 610,834, which resulted in Patent No. 1,286,323, on a machine for making stereotype plates, patented December 3, 1918.

This invention is for the purpose of cooling semi-circular curved stereotype printing plates for use on the cylinders of rapid printing or rotary presses, particularly such 20 as are in common use in producing newspapers, and is designed mainly as a labor saving device whereby one man by manipulating certain handles and levers will be able to produce the stereotype printing plates 25 completely finished, and cooled so they can be handled by the bare hands, in condition to be immediately attached to the printing press cylinder, and especially to provide an improved method whereby through the control 30 of the contraction of the curved printing plate during the process of cooling, the operator will be able to produce plates of various curvatures or dimensions from the same casting chamber and further, through the control 35 of the cooling fluid, deliver the plates practically dry and ready to be attached to the press cylinder; also to provide for controlling the flow of cooling water itself.

Further objects and advantages of the invention will appear hereinafter.

Reference is to be had to the accompanying drawings in which—

Fig. 1 is a side elevation of a cooling machine constructed in accordance with this 45 invention;

Fig. 2 is a fragmentary detail thereof;

Fig. 3 is a sectional view of the same on the line 3—3 of Fig. 1;

Fig. 4 is an enlarged sectional view on the 50 same line showing how the edge of the plate is held during one period of the operation;

Figs. 5 and 6 are similar views showing other positions of the plate, and

Fig. 7 is an end view of one of the rollers for supporting the plate with parts in section.

This invention is concerned with the treatment of a curved stereotype printing plate after it has been cast, finished, and delivered by such a machine as is shown in my above 60 mentioned Patent No. 1,286,323 or in any other way. Assuming that the plate has been delivered in any desired way I will now describe the improved flexible cooling and drying mechanism employed, and explain how 65 by controlling the contraction of the stereotype plate during the cooling process I am able to produce plates of both less or greater diameter from the same casting chamber, also how by the control of the cooling water 70 I can produce the plate dry and ready for the press cylinders.

Curved stereotype plates, such as are used in producing newspapers, are of a semi-circumference equal to the length of the printed matter of a newspaper page, and vary in diameter from $13\frac{1}{2}$ to $16\frac{1}{2}$ inches.

It is often found that, although the printing faces of two different makes of web perfecting presses are the same yet the cylinders 80 may vary in diameter an eighth of an inch, more or less, the difference being in the margins or space between the two printing halves of the circumference of the cylinders which form the top and bottom blank space 85 or margins of the paper.

Owing to this variation heretofore it has been necessary to cast the plates in machines for each size, and again owing to there being a large variety of sizes of presses between the $13\frac{1}{2}$ and $16\frac{1}{2}$ inch size (about 20) it 90 has been considered impracticable to carry casting and finishing machines in stock. These difficulties I am now able to overcome.

I find that an average sized curved stereotype plate will suddenly contract about $\frac{1}{2}$ " in diameter when the cooling water engages its concavity, and as the cooling advances from the concave side through to the exterior the plate will slowly contract on the outside 95 and counteract the interior contraction, and if left perfectly free the plate will resume 100

its normal curvature. However if the curved plate is supported in a manner so its straight edges are held against axial contraction during the cooling of the interior surface it will nevertheless contract on the exterior and through this contraction cause the straight edges of the plate to draw away from its axis and thereby become of a larger diameter than when cast. By utilizing and controlling this contraction I am able to produce plates of all sizes from four sizes of stock machines.

To accomplish this control of the contraction I have made a cooling saddle with flexible sides or wings 71 arranged so as to contract or expand with the plate during the cooling operation, the wings 71 are composed of spring metal, and are normally of a curvature slightly smaller than the diameter of the concave face of the finished ribs P' on the interior of the stereotype plate P. They are fixed to the sides of an overflow outlet 73 of a water distributing chamber 74 which is supported by pivots 75 on the frame G. The water chamber 74 is connected by a flexible tube 76, to a supply pipe 77 and a water controlling valve 78.

At each straight side of the wings are mounted rollers 80 for supporting the stereotype plate as it is delivered by gravity from the finishing mechanism. Also mounted on each straight side of the wings are brackets 81 which extend beneath the edges of the stereotype plate and have a lip 82 extending up so as to engage the outside edge of the stereotype plate. Beneath the wing brackets and supported by the frame are adjustable stops 83 which engage grooves 84, in the underside of the wing brackets 40 when the stereotype has contracted or expanded the required amount as hereafter described.

The pivoted cooler, plate rollers, and brackets are normally held on the same angle as the main shaft of the finishing mechanism F by a spring 86 attached to an arm 87 fast to the pivot 75, and a pivoted latch 89, is arranged to hold it at that angle during the delivery of the stereotype plate, but 50 as the same plate positions itself by sliding down over the rollers from the finishing mechanism the beveled end of the plate engages the said latch and lifts it up. This releases it from engagement with the cooler 55 whereupon the cooler and plate will turn to horizontal position owing to the greater portion of the stereotype plate being beyond the pivot point. When the plate is lifted by hand from the cooler the spring 86 rocks the cooler back to the inclined receiving position shown in Fig. 1.

The balanced valve 78 is positioned in the water connections so that its plunger 91 can be operated by a lever 92 attached to the

pivot 75, of the cooler. To one end of the 65 plunger is fastened a rod 94, operating in a bearing. It is provided with a spring actuated latch 95 in the path of a pin 96, positioned upon the lever 92 so that when the cooler turns on its pivot the pin engages the 70 latch and opens the valve allowing the water to flow up into the cooler water distributing chamber and overflow between the hot stereotype plate and flexible wings. As the outlet for the water is confined to the space between the wings 71 and concave face of the stereotype plate, which space is less in cross section than the inlet, the water will be held under pressure against the stereotype plate and drive ahead any steam that may form, 80 thereby causing very quick action in cooling the stereotype plate. A stop 99 limits the rocking of the saddle.

For the purpose of stopping the flow of water before the stereotype plate is entirely 85 cold and allowing it to drain free from the plate so that the heat remaining will evaporate any moisture remaining, any desired construction can be used as for instance a valve which opens automatically in a given 90 time, but I have shown a friction driven timing mechanism composed of a wheel 20 mounted on a stud 21 on an arm 22. This arm is pivoted to the frame G, by a stud 23. This wheel is intermittently driven by 95 a small pin 24, axially mounted on the end of the worm cross shaft 31. Normally facing this pin is a recess 26, formed across the face of the wheel. To the side of the wheel is fixed a pin 27 which is engaged by a projection 28 formed on the lower end of the arm 92, and positioned so that as the cooler turns to horizontal position it will cause the said projection to engage the pin and turn the wheel ahead so that pin 24, normally revolving in the recess 26, engages the face of the wheel 20 and causes said wheel to make one revolution. At the end of the revolution a second pin 30 engages and trips the valve plunger latch 95, which 100 action causes the valve to close and the flow of water to stop. A drip opening 32 is positioned near the over flow of the cooler which allows all water above the said drip to escape so that when the stereotype plate 115 is being lifted, (which action allows the cooler to be turned by its spring 86 into alignment with the main shaft and in position to receive the following stereotype plate), there is no danger of splashing the 120 stereotype which is now cooled and dried.

By this combination of water control I not only require less water, as by actual test a plate can be sufficiently cooled after a water contact of three seconds, and a draining and evaporating lapse of three seconds more, but also I succeed in cooling the stereotype plate so it can be removed from the 125

cooler by the bare hands. This regulation of the water dispenses with brushes or any other means of wiping the plate dry as has been the practice heretofore.

5 During the cooling operation, as stated, the stereotype plate contracts first on the interior and then, as the cooling advances through the plate on the exterior. This is due to the cooling water engaging the 10 cavity of the stereotype only.

The means employed for controlling the contraction as previously stated comprises adjustable stops 83 which engage the brackets 81 attached to the flexible wings of the 15 cooler, the stereotype plate being held against the wings by projections 82 on the bracket overlapping the straight edges of the stereotype plate. So if it is desired to reduce the curvature the adjustable stops are

20 axially moved to the diameter desired so when the hot plate rolls down over the cooler and trips the latch 89, the cooler turns on its pivot until the bracket 81 engages the top of the adjustable stop as shown in

25 Fig. 4. The act of tipping the cooler having opened the valve, the water rushes into contact with the concave side of the stereotype plate which causes the inside of the stereotype plate to contract, thereby reducing

30 the diameter. This causes the wings carrying the grooved bracket to move axially inward until the groove 84 is just above the adjustable stop, whereupon the weight of the stereotype plate causes the cooler to 35 turn on its pivots. This allows the stop to enter and engage the groove, as shown in

Fig. 5 thereby holding the stereotype plate and wings against any further flexing of the stereotype plate in either direction, and 40 thereby leaving the stereotype of a less diameter than when cast. To cause the stereotype to be of a greater diameter after cooling than when cast, the adjustable stop 83 is moved axially out to the desired diameter.

45 See Fig. 6. If the full limit of expansion is required the stop is moved so it will engage the projection 39 on the lower side of the bracket 81 which will prevent any interior contractions, but as the exterior cools the

50 contraction on the outer side will cause the stereotype plate to open out until the lip of the adjustable stop engages the groove as in the opposite direction. See Fig. 5. However, if a lesser expansion of the diameter

55 is desired the stop should be moved out less. Then the action will be, first an interior and closing-in contraction which will cause the projection 39 on the bracket to engage the stop 83, and upon the exterior con-

60 traction taking place the stereotype plate will expand until the lip of the adjustable stop enters the groove of the bracket and resists further expansion of the diameter of the stereotype plate. If the plate is cooled

on the exterior instead of on the interior 65 the process will be modified accordingly.

Beneath the cooler a sink 40 is formed for catching the waste water which sink is provided with a pipe 41 for carrying the water away. 70

The cooling apparatus is not claimed herein as it is included in my above mentioned application Serial No. 159,117.

While I have illustrated and described a preferred embodiment of the invention I am 75 aware of the fact that many modifications can be made therein by any person skilled in the art without departing from the scope of the invention. Therefore I do not wish to be limited to all the details of construction herein shown and described except as 80 defined in the appended claims, but what I claim is:—

1. A method of cooling curved cast plates to control the diameter thereof, which consists in applying a cooling fluid to one 85 curved surface of a plate and preventing its contact with the other curved surface thereof, and positively controlling the contraction and expansion of the plate by limiting 90 the motion of the straight edges of the plate toward or from each other.

2. A method of cooling curved stereotype printing plates which consists in applying a cooling fluid to the interior concave 95 surface thereof and preventing its application to the exterior surface, allowing the opposite straight edges to approach each other at will by contraction and then limiting the subsequent drawing apart of said edges. 100

3. A method of cooling curved stereotype printing plates which consists in applying a cooling fluid to the interior concave surface thereof and preventing its application to the exterior surface, allowing the opposite straight edges to approach each other at will by contraction and then limiting the 105 subsequent drawing apart of said edges by expansion whereby the plate produced will be smaller in diameter than the plate as cast. 110

4. A method of cooling and drying a curved stereotype printing plate which consists in applying a cooling water thereto to partly cool the plate, then discontinuing the application of cooling water and allowing 115 the plate to continue to cool whereby the heat remaining in the plate will evaporate the water on the surface thereof and dry it.

5. A method of cooling curved stereotype printing plates, which consists in applying 120 a cooling fluid exclusively to the interior of said plates and distributing it along the entire interior surface, positively limiting the extent of contraction of the plate inwardly toward the axis thereof, and then allowing 125 the cooling of the plate to extend through the plate and permitting free expansion of the plate outwardly.

4

6. A method of cooling curved stereotype printing plates, which consists in applying a cooling fluid to the interior concave surface thereof and preventing the contact of said fluid with the exterior surface, limiting the drawing together of the straight edges of the plate by contraction during the first

part of the cooling operation and then allowing them to draw apart by the subsequent expansion, whereby the cooled plate will be 10 of larger diameter than the plate as cast.

In testimony whereof I have hereunto affixed my signature.

CHARLES E. HOPKINS.
